US00D914317S

(12) **United States Design Patent** (10) **Patent No.:** **US D914,317 S**
(45) **Date of Patent:** **** Mar. 23, 2021**

(54) **SHOPPING CART**

(71) Applicant: **Retail Design Services, LLC**,
Northfield, MN (US)

(72) Inventors: **John Robert Ebling**, Northfield, MN
(US); **Gary Robert Ebling**, Northfield,
MN (US)

(73) Assignee: **Retail Design Services, LLC**,
Northfield, MN (US)

(**) Term: **15 Years**

(21) Appl. No.: **29/680,124**

(22) Filed: **Feb. 13, 2019**

(51) LOC (13) Cl. **12-02**

(52) U.S. Cl.

USPC **D34/21**

(58) **Field of Classification Search**

Westman, Champlin & Koehler, P.A.

(57) **CLAIM**

The ornamental design for a shopping cart, as shown and described.

DESCRIPTION

FIG. 1 is an isometric view of a shopping cart;

FIG. 2 is a front end view thereof;

FIG. 3 is a rear end view thereof;

FIG. 4 is a side view thereof as taken from the right side of

FIG. 3, the other side view is a mirror image thereof;

FIG. 5 is a top view thereof; and,

FIG. 6 is a bottom view thereof.

The broken lines in the drawings depict portions of the shopping cart that form no part of the claimed design.

1 Claim, 6 Drawing Sheets
